UNITED STATES PATENT OFFICE.

JOHN R. PERFATER, OF HAMPTON, VIRGINIA.

GLARE-PREVENTING ATTACHMENT FOR HEADLIGHTS.

Application filed June 3, 1925. Serial No. 34,549.

To all whom it may concern:

Be it known that I, JOHN R. PERFATER, a citizen of the United States, residing at Hampton, in the county of Elizabeth City 5 and State of Virginia, have invented certain new and useful Improvements in Glare-Preventing Attachments for Headlights, of which the following is a specification.

This invention relates to glare preventing 10 attachments for headlights, and the primary object thereof is to provide an improved type of attachment which can be easily and quickly fitted or applied to the headlight by the purchaser, and which is positively held 15 in position against lateral or other shifting movements.

In the drawings:-

Fig. 1 is a front elevation, partly broken away and in section, showing the invention 20 applied to a headlight;

Fig. 2 is a section on line 2—2 of Fig. 1; and

Fig. 3 is a side elevation of the invention 25 detached from the headlight.

In proceeding in accordance with the present invention, a translucent glare-preventing member 1, preferably of colored celluloid, is employed. The member 1 is of segmental shape and is provided at its inner end with 30 an opening 2 to receive the usual socket 3 of the electric lamp L. The surface of the member is shaped to generally conform to that of the parabolic reflector 4. The outer end of the member is formed with a series of 35 spaced cuts, forming a corresponding series of fingers 5. The member is originally formed of a length in excess of the requirements, so that any variations in the radii of the reflector, can be compensated for.

In certain types of headlights, packing, in 40 the form of cord 6, is employed to cushion the front lens, the present invention being designed for use with such types.

In order to apply the attachment, the electric lamp is removed, the modifier applied 45 and the lamp then replaced. The modifier is forced into firm surface contact with the parabolic reflector in which position the fingers 5 will overhang the front edge of the reflector. The front edge of the reflector is now used as a form and the fingers 5 are bent downwardly thereabout. If the fingers are too long same may be easily cut with scissors. The cord is now sufficiently disengaged 50 from its holding groove to permit

preferably the endmost fingers 5' to be disposed to the rear of the cord, the remaining fingers being disposed to the front of the cord. The front lens F is then repositioned, and the latter firmly forces the cord against 60 the endmost fingers 5', and into the packing groove 8, automatically conforming or shaping same to agree with the cross-sectional curvature of the groove. Thus the light modifier is firmly held in position, the fingers 65 being engaged on opposite sides of the cord and being clamped between the latter and the lens and the reflector front edge. Due to the spacing of the fingers, same further are clamped in position at a plurality of 70 points. The curvature imparted to the endmost fingers 5' causes same to be interlocked 75 in the packing groove, or to be virtually hooked into engagement with the groove and packing, effecting positive and fixed secure- 75 ment of the member 1 holding same firmly against movement.

What is claimed is:

1. In combination with a headlight and the cord packing thereof, a glare preventing 80 attachment composed of a substantially segmental body having an opening at its inner end to receive the headlight lamp socket, and having a series of spaced fingers at its outer end, the endmost fingers being engaged on the rear of the packing and the remaining fingers on the front of the packing, said fingers being formed of yieldable material whereby upon engagement of the headlight lens with the fingers and packing the 85 latter will force the endmost fingers into the packing groove and conform same in shape thereto.

2. In combination with a headlight and the cord packing thereof, a glare preventing 90 attachment composed of a substantially segmental body having an opening at its inner end to receive the headlight lamp socket, and having a series of spaced fingers at its outer end, some of the fingers being engaged 95 on the rear of the packing and others on the front thereof, the fingers being yieldable whereby upon engagement of the headlight lens with the packing the latter will force the fingers on the rear of the packing into 100 the packing groove and conform same in shape thereto.

In testimony whereof I affix my signature.

JOHN R. PERFATER.
